Primary Examiner — Cynthia M. Chin(57) **CLAIM**

The ornamental design for a hinged toy brick attachment panel, as shown and described.

DESCRIPTION

FIG. 1 is a front perspective view of a hinged toy brick attachment panel showing my new design;

FIG. 2 is a rear perspective view of the hinged toy brick attachment panel;

FIG. 3 is a front side view of the hinged toy brick attachment panel;

FIG. 4 is a rear side view of the hinged toy brick attachment panel;

FIG. 5 is a right side view of the hinged toy brick attachment panel, a left side view being a mirror image thereof; and, FIG. 6 is a top view of the hinged toy brick attachment panel, a bottom view being mirror image thereof.

The broken lines shown are included for the purpose of illustrating portions of the article which form no part of the claimed design.

1 Claim, 5 Drawing Sheets(56)
